UNITED STATES PATENT OFFICE.

LOUIS J. DIEU, OF SOUTH SAN FRANCISCO, CALIFORNIA.

VAPOR BURNER.

Application filed June 7, 1926. Serial No. 114,362.

The present invention relates to improvements in vapor burners and has particular reference to vapor burners adapted for use in connection with furnaces in general and particularly with furnaces used in foundries, steam boilers and the like.

Vapor burners for use in connection with foundry furnaces and the like are exposed to the action of intense heat and their use frequently is limited to very short periods. Constructions have heretofore been proposed for cooling these burners by water but this has been ineffective due, undoubtedly, to the absence of means for properly circulating the water and to other defects in the construction of the burners themselves.

Coming now to the present invention, the general object thereof is the provision of a water cooled burner which is characterized by the provision of a plurality of concentrically disposed jackets around the vapor passage of the burner, together with means for effecting the flow of cooling mediums through the said jackets.

Another object is to provide for increasing the efficiency of the burner in and around the tip thereof by the provision of a construction which operates to reduce, if not entirely prevent the forming of carbon in the opening of the tip.

A further object is to provide for the effective mixing or carburation of the combustible fluid.

The above and other objects are accomplished by instrumentalities pointed out in the following specification.

The invention is clearly defined in the claim.

A satisfactory embodiment of the invention is illustrated in the accompanying drawings forming part of the specification and in which

Figure 1 is a contracted vertical longitudinal section of the complete burner.

Figure 2 is a contractive plan view of the same with a fragment of the forward end portion of the wall removed to disclose a portion of the interior construction.

Figure 3 is a vertical cross section on the line 3—3 of Figure 1, looking in the direction of the arrows, and

Figure 4 is a view similar to Figure 3 taken on the line 4—4 of Figure 1 and looking in the direction of the arrows.

The burner of the present invention comprises a stock *a* and a barrel *b*. The stock

is an oblong metallic casting formed with an opening 5 for connection to a suitable bracket for supporting the device in operative position. The forward end portion of the stock is shaped so as to fit into the barrel and the parts are welded together so as to provide a permanent fluid-tight joint. The rear end portion of the stock *a* is formed with an obliquely disposed nipple 6 adapted as by having an exterior screw threaded surface for connection to a hose coupling for conveying compressed air, steam or the like to mix with the fuel vapor within the stock *a*. The passage through the nipple is in alignment with the mixing passage 8 which extends upwardly and forwardly through the stock and to a point at approximately the middle portion thereof, whence the passage is directed downwardly and forwardly as at 9 and terminates in the forward extension 10 disposed axially or substantially so of the stock. A nipple 11 is formed with the stock *a* and is disposed preferably above and in angular relation to the nipple 6. The nipple 11 is adapted for connection to the coupling of a conduit for conveying liquid fuel to the burner. The passage through the nipple is in alignment with a liquid fuel passage 12 in the rear end of the stock and terminating in the passage 8. With this construction the upward flow of compressed air or steam through passage 8 entrains the gas or other liquid fuel in passage 12 and operates to effectively combine therewith.

The combination between the components of the combustible mixture is then further refined by the contour of the entire passage made up of the portions 8 and 9 in that the direction of the flow of combustible mixture from the portion 8 is changed by virtue of the location of the portion 9 so that at the junction of these passages, the combustible mixture is agitated on being required to follow a change in the direction of flow so that a thorough commingling of the components of the mixture is effected.

A chamber 13 is disposed at the meeting ends of the portions 8 and 9 and the diameter of this chamber is longer than the diameter of either of the passages 8 and 9 so that a portion of the wall of the chamber is disposed in the path of the combustible mixture flowing through the passage 8 and thereby provides an abutment. The presence of this abutment operates to break up the mixture and more uniformly distrib-

ute the components thereof when the mixture impinges upon the wall.

A supplemental air passage 14 is disposed forwardly of the passage 8 and extends into the axial extension 10 of the passage 9 and a nipple 15 surrounds the outer end of this passage and is formed integral with the stock and adapted for connection to a supply of air or steam if so required. A removable 10 plug 16 is screwed or otherwise detachably secured in the upper end portion of chamber 13 and forms a closure therefor. When the plug is removed, a suitable instrument may be inserted into either of the passages 8 15 and 9 for the purpose of cleaning the same.

The barrel *b* has a centrally disposed tube 17 which conveys the combustible mixture to the tip as shown, the said tip being connected in the ordinary manner to the screw 20 threaded portion 18 at the forward end of the tube. As shown the tube is in axial alinement with the extension 10 of passage 9 and is seated in a circular recess 19 in the forward end of the stock *a*. A circular rib 25 20 forming the recess 19 provides a bearing surface for an intermediate tube 21 surrounding and concentric with the tube 17 and spaced therefrom so as to provide an air jacket 22. The tubes 17 and 21 may be 30 welded to the stock as shown. Tube 21 extends forwardly and beyond tube 17 and spacers 23 are provided for supporting the forward end portion of tube 21. A tubular connection 24, preferably of annular contour, 35 is directed into the air jacket 22 and exteriorly it is provided with a nipple 25 for connection to a supply of compressed air or steam which is permitted to flow forwardly through the air jacket and into the chamber 40 25 for the tip, not shown. With this construction a flow of compressed fluid is provided for commingling with the flame at the tip and, at the same time, the action of this current of air or steam in moving over the 45 surface of the tip operates to remove carbon deposits that may form thereon.

An outer tube 26 surrounds the tube 21 and the rear end portion of this tube receives a circular boss 27 forming the forward end 50 portion of the stock *a*. The tube 26 and stock are preferably connected together by welding, and the boss operates to support the tubes 21 and 26 in spaced relation, and the intervening space 28 provides a water 55 jacket for the barrel. The forward end of

the tube 26 is connected by an annular wall 29 to the forward end of tube 21, and this wall provides a fluid-tight fit for the forward end of jacket 28.

A pair of oppositely disposed division 60 walls 30 and 31 extend longitudinally through the water jacket 28, their rear ends being welded to the stock *a* and their forward ends terminating short of the front wall 29 as clearly shown in Figure 2. The 65 walls are disposed so as to interiorly divide the water jacket into upper and lower compartments which communicate only at the forward end portion, as stated, the sides of the division walls being welded to the adjacent surfaces of the tubes 26 and 21. A nipple 32 depends from the rear end portion of outer tube 26 and an oppositely disposed nipple 33 extends vertically upward from the tube. These nipples are adapted for connection to the coupling of a hose for conveying water from a suitable source into the water jacket. The water upon entering into the inlet nipple 32 passes through the lower compartment of the water jacket and upwardly 80 and into the upper compartment and outwardly through the outlet nipple 33.

Thus it is to be seen that when the burner is in operation, a low temperature is insured by the presence of the water jacket and the 85 intervening air jacket, so that the defect in burners of this type, due to overheating of the barrel, is effectively avoided.

Although I have shown and described one embodiment of my invention, it is to be understood that the same is susceptible of various changes; and I reserve the right to employ such as may come within the scope of the appended claim.

What I claim is:

A vapor burner comprising a barrel, a stock having an inlet end portion and an outlet end portion and a longitudinally disposed passage connecting said outlet and inlet portions, the outlet end portion of said stock being connected to one end of the barrel, the said barrel including a central tubular portion, an open ended air jacket surrounding the same and a water jacket surrounding the air jacket and interiorly divided into two compartments communicating adjacent to the free end portion of the barrel, one of said compartments having an inlet and the other an outlet.

LOUIS J. DIEU.
